UNITED STATES PATENT OFFICE.

ROBERT ZAHN, OF PLAUE, GERMANY; ALFRED RIETZSCH ADMINISTRATOR OF SAID
ZAHN, DECEASED.

FABRIC-FRAME-MOTION MECHANISM.

1,127,148.

Specification of Letters Patent.

Patented Feb. 2, 1915.

Application filed January 23, 1913. Serial No. 743,846.

To all whom it may concern:

Be it known that I, ROBERT ZAHN, a subject of the German Emperor, residing at Plauen, in Vogtland, in the Kingdom of 5 Saxony, Germany, have invented certain new and useful Improvements in Fabric-Frame-Motion Mechanism, of which the following is a specification.

To obtain a perfect motion of the fabric 10 frame in embroidering machines, an ideal arrangement would be one, whereby all parts of the fabric frame are forced to carry out motions that with mathematical precision correspond to the motions of the 15 point at which the pantograph or jacquard mechanism actuates the frame. It has already been tried to provide mechanisms whereby positive motion is transmitted to a point of the fabric frame located diagonally opposite the point actuated by the 20 pantograph or jacquard. Thus for instance, if the jacquard acts on a point at the left lower corner of the fabric frame the right upper corner thereof receives positive motion. Such arrangement, of course, could 25 be regarded as perfect, had it not been for the fact that the fabric frame is not an absolutely rigid body, but to a certain extent flexible. Because of the flexibility of 30 the fabric frame, the movements of the different points between the corners thereof vary more or less from those of the latter.

To obviate this drawback is the object of 35 my invention, which I accomplish by a special motion transmitting mechanism.

One embodiment of my invention is more or less diagrammatically illustrated in the accompanying drawing in which similar parts are denoted by corresponding reference characters.

In the drawing 1 denotes the fabric frame and 1' may be a point of the upper longitudinal bar thereof at which the frame is most flexible. The fabric frame in well 45 known manner is positively acted upon by the jacquard 3 through the medium of a rack 2. Experience has taught that the transmission of positive short movements to heavy masses such as the fabric frame can 50 be best obtained through the medium of taut steel bands, straps or like draft members and for this reason, in the present embodiment of my invention, I provide steel bands which intersect one another and

are fixed at their ends, as will hereinafter 55 be specified. These bands are guided over pulleys 8 and 9 respectively, which by ball bearings (not shown) are supported in stationary parts 8', 9' of the machine frame. The ends 4 and 6 of the two bands are fixed 60 to the upper part 10 of the rack 2 and the points 5 and 7 are fixed to the ends of a vertical reciprocating bar 15 arranged adjacent to the arbitrarily chosen intermediate point 1' of the fabric frame. The 65 rack 2 meshes with a pinion 11 driven from the jacquard 3 in well known manner and receives therefrom a vertical reciprocatory motion. The vertical movement of the fabric frame is transmitted through the medium 70 of a loop 12 formed on the rack 2 and engaging a roller 14 carried by an arm 13 of the fabric frame. The bar 15, too, is formed at its lower end with a corresponding loop 75 16 in which movably engages a roller 17 carried by a projection 1² provided at the point 1' of the fabric frame 1. Owing to this positive connection the center of the roll 17 executes precisely the same vertical movements as the center of the roll 14 to 80 which motion is directly transmitted from the jacquard through the rack 2. By virtue of this construction, the mechanism for transmitting motion to the fabric frame approaches nearest the ideal sought for. During 85 the horizontal movements of the fabric frame the rollers 14 and 17 roll in the loops 12 and 16 of the fabric guide members 2 and 15 respectively.

What I claim and desire to secure by Letters Patent is:

1. In an embroidering machine, a fabric frame, a driven vertically slidable member engaging a point at one end of the said fabric frame, a vertically slidable member 95 engaging a point located intermediately between the ends or corners of said fabric frame and flexible draft members positively connecting said vertically slidable members to transmit uniform movements to 100 said frame.

2. In an embroidering machine, a fabric frame, a driven vertically slidable member engaging a point at one end of said fabric frame, a vertically slidable member engaging a point of the fabric frame located intermediately between the ends or corners thereof, and flexible draft members posi- 105

tively connecting said vertically slidable members to transmit uniform movement to said fabric frame.

3. In an embroidering machine, a fabric frame, a driven vertically movable guide member for a point at one end of the said fabric frame, a vertically movable guide member for a point of the fabric frame located intermediately between the ends or 10 corners thereof and crossing flexible members positively connecting said guide members to transmit uniform movement to said fabric frame.

4. In an embroidering machine, the combination with the stationary frame, of a 15

fabric frame, a driven vertically movable guide member for a point at one end of the said fabric frame, a guide member for a point of the fabric frame located intermediately between the ends or corners thereof and vertically movable in said stationary frame and crossing flexible members positively connecting said movable guide members. 20

In testimony whereof I affix my signature in presence of two witnesses. 25

ROBERT ZAHN.
